UNITED STATES PATENT OFFICE.

JOHN S. BOYD, OF WILLIAMSTOWN, MASSACHUSETTS, ASSIGNOR TO JOHN S. BOYD CO. INC., OF WILLIAMSTOWN, MASSACHUSETTS, A CORPORATION OF MASSACHUSETTS.

TEXTILE FABRIC.

Application filed April 10, 1923. Serial No. 631,177.

To all whom it may concern:

Be it known that I, JOHN S. BOYD, a citizen of the United States, and resident of the town of Williamstown, county of Berkshire, 5 and State of Massachusetts, have invented a certain new and useful Improvement in a Textile Fabric, of which the following is a specification.

The object of this invention is to provide 10 a textile pile fabric of an ornamental form so arranged and constructed that its pile sections or areas are located at spaced intervals whereby the base fabric upon which the pile areas are produced may be visible 15 at positions intermediate of the pile areas.

By arranging the pile areas at different positions upon the base fabric from which they project, various highly ornamental designs may be produced.

20 A further object of this invention is to provide an ornamental pile fabric which may be readily constructed by a simple process of eliminating certain portions of thread which produce the pile whereby those portions of the base fabric upon which the pile 25 is formed are rendered visible and act to separate the various pile sections or areas and contrast therewith.

By the use of threads of contrasting colors 30 for producing the pile and its base or background, very pleasing ornamental effects are produced.

A still further object of my invention is to provide a pile fabric of extremely light 35 weight. The various forms of pile fabric in use at the present time such as velvet and corduroy are of substantially heavy weight and thickness and consequently are applicable for use at certain seasons of the year.

40 A pile fabric made in accordance with my invention is of exceptional light weight which renders it highly desirable for all uses to which a light weight pile fabric may be required.

45 With these objects and other objects which may hereinafter appear, in view, I have devised the particular arrangement of parts hereinafter set forth and more particularly pointed out in the claims appended hereto.

50 Reference is to be had to the accompanying drawing forming a part hereof in which—

Figure 1 is a plan view of a section of my fabric in its primary state.

Figure 2 is a sectional view on the line

2—2 of Figure 1 looking in the direction 55 of the arrows.

Figure 3 is a view of the underside of the fabric disclosing in detail the woven under fabric or base and the manner in which the pile fabric threads interengage certain 60 threads therewith which act as binder stitches.

Figure 4 is an enlarged view of a fragment of the fabric showing the interengagement of the pile fabric threads with the 65 binder threads.

Figure 5 is a view of the underside of the primary fabric after certain pile threads have been eliminated.

Figure 6 is a plan view of the fabric in 70 its second stage after portions of the pile threads have been eliminated and just prior to the process of consolidating the remaining pile threads to form the spaced sections or areas of pile which remain as part of the 75 fabric.

Figure 7 is a sectional view of the fabric in the form disclosed in Figure 6.

Figure 8 is a perspective view showing the binder threads and the interengagement 80 of the pile fabric threads therewith.

Figure 9 is a plan view of the finished fabric showing one of the patterns which can be produced, and

Figure 10 is a sectional view of the same. 85 Throughout the various views of the drawings, similar reference characters designate similar parts.

In the embodiment of my invention as disclosed herein, I will describe the manner 90 in which a specific form or pattern of my improved fabric is produced. Other patterns are produced by following the same method of procedure with slight rearrangement and spacing of the pile fabric threads 95 and the binder threads which hold them to the woven base fabric.

In the accompanying drawing, the base fabric is disclosed at 1 and it will be seen that the same is composed of a section of 100 woven material.

The pile producing threads 2 are a plurality of threads which are located on one face of the base fabric 1 and are connected thereto at certain spaced intervals, which 105 connection is established by inter-weaving the pile fabric producing threads 2 with certain threads in the base fabric which for

convenience will be hereinafter designated as the binder threads.

The binder threads as above mentioned serve to attach the pile producing threads 5 to the base fabric and it is the location of these binder threads with respect to one another which determines the location of the various sections of pile and consequently the pattern to be produced on the fabric.

10 It will thus be seen from the foregoing that the pile producing threads consist of a plurality of looped threads which are placed adjacent one another and cover one surface of the base fabric and are connected thereto 15 at spaced intervals. The binder threads are disclosed at 3, and the pile threads inter-engage with said binder threads 3 as shown.

To form the pattern disclosed in Figure 9, the binder threads are located as shown 20 in Figure 1, that is, in substantially staggered relationship. With the fabric in this state, which I will designate the primary state, the cutting process then takes place.

In Figure 1, the dotted lines disclosed 25 at 4 indicate the lines on which suitable knives cut the pile fabric threads 2 without of course penetrating or cutting the base fabric 1.

It will be seen that when knives cut along 30 the lines indicated at 4, those pile threads which are located intermediate of said lines and which are not held down on the base fabric by means of the binder threads 3, may be readily picked away or eliminated 35 from the base fabric 1 so that said base fabric will be visible.

Thus, those portions of the pile threads which are indicated at 5 and 6 in Figure 1 40 are removable from the fabric after the cutting operation takes place leaving the fabric then in the condition disclosed in Figures 5, 6 and 7.

The binder threads 3 will retain attached to the base fabric 1, certain pile threads 7 45 (Figs. 6 and 7) which by subsequent treatments are formed into blocks or areas of pile indicated at 8 in Figures 9 and 10. The threads indicated at 7 are brushed together, singed, washed, dyed and otherwise treated 50 in the manner customary in connection with pile fabrics and when these treatments are completed, the finished product disclosed in Figures 9 and 10 results, that is, a fabric is produced which is provided with spaced 55 areas of the pile between which are visible the base fabric 1 which may be if desired, of substantially open mesh to provide a cool, light weight fabric.

It will be seen that various patterns may 60 be produced by the simple location of the binder threads and the manner in which they engage with the base fabric 1.

A further element in the production of 65 various patterns resides in the positions at 68 which various pile threads are eliminated

from the primary fabric. This fabric may be produced in various weights, thicknesses and weaves and many highly ornamental fabrics may be made by the utilization of threads of various colors, silk and cotton 70 mixtures and the like.

From the foregoing, it is obvious that my invention is not to be restricted to the exact embodiment shown but is broad enough to cover all structures coming within the scope 75 of the annexed claims.

What I claim is:

1. A textile fabric comprising a woven base fabric having a plurality of looped threads secured to it and arranged on its front face, the points of securement of some of said threads to the base fabric being located intermediate of the points of securement of other of said threads, portions of said looped threads being adapted to form pile areas and other portions of said threads being adapted to be cut between their points of attachment to the base fabric and removed to render visible portions of the base fabric located between the pile areas. 80

2. A textile fabric comprising a woven material having a plurality of threads extending across its front face in a series of loops, said threads being interwoven with the body of the material at spaced intervals, 85 the points of securement of some of said threads being located intermediate of the points of securement of other threads whereby portions of said loops can be removed from the front face of the fabric when a 90 pair of parallel cuts are made transversely of the loops.

3. A textile fabric comprising a woven base material, a series of threads extending across the same and connected to the base 105 at spaced intervals by binder threads and forming independent groups, some of said groups of threads being arranged in staggered relationship to other groups and looped over the binder threads of said other 110 groups whereby a knife cut across the threads on opposite sides of the points of securement of some of the groups of threads to the base material will detach from the base, portions of the threads of other groups. 115

4. A textile fabric comprising a woven base material, groups of looped threads arranged on one face of the base material and connected thereto by binder threads in the base, other groups of threads adapted to 120 pass over the binder threads of the first mentioned groups, said threads having portions adapted to be detached by parallel cuts of a pair of knives and portions adapted to be held on the base by binder threads to form 125 pile areas.

Signed at Williamstown, county of Berkshire and State of Massachusetts, this 23 day of March, 1923.

JOHN S. BOYD.
